tion of Ohio

Application July 22, 1949, Serial No. 106,219

18 Claims. (Cl. 232—44)

1

My invention or discovery relates to night depository construction of the type used particularly by banks and which includes a door mounted on the outside of the wall of a bank, and in which the door has a key-operated lock. Depositors are provided with keys for the door and each depositor uses one of these keys in making a deposit. The door may have a pivot mounting and from the rear of the door there extends a hopper in which the deposited article in any form such as a bag or package of money may be placed when the door is open. When the door is closed the deposited article should fall from the hopper and slide down a chute into the bank vault.

In such a usual night depository construction, robbers have obtained a key to the door, and have opened the door and suspended wires or cords having a bag or hooks on their lower ends which are suspended in the chute. The door is then closed and the wires or cords are led out of the door frame in an unobserved manner. The next deposited article is caught by the suspended bag or hooks without the knowledge of the depositor. The robbers then return and open the depository door again and fish up the suspended bag or hooks in which the deposited article has been caught.

The objects of the present invention or discovery include the provision of an improved night depository construction of the type including a pivoted door and a hopper extending from the rear of the door, and which includes parts cooperating with the door and the hopper in such manner that the chute opening at all times is substantially closed off whether the depository door is open or in the course of being closed or in the course of being opened.

Further objects of the present invention or discovery include the provision of such an improved night depository construction in which after a deposited article has been placed in the hopper when the door is open, it is necessary for the door to be entirely closed without possibility of reopening in order that the deposited article shall drop down the chute.

Further objects of the present invention or discovery include the provision of such an improved night depository construction in which a deposited article is forcibly ejected from the hopper into the chute, and in which even if by some means there has been suspended in the chute a bag or hooks on which the deposited article is caught, the deposited article will become wedged in a manner preventing opening of the door.

Further objects of the present invention or dis-

covery include the provision of such an improved night depository construction in which the hopper includes a bottom wall fixed with respect to the door, and in which there is a swinging bottom wall in the hopper pivoted at the rear end of the fixed bottom wall, and in which cam track and cam follower means actuated by opening and closing of the door cause movement of the swinging bottom wall for the attainment of the previously defined objects.

The foregoing and other objects are attained by the night depository construction, improvements, members, parts, combinations, and sub-combinations, which comprise the present invention or discovery, the nature of which is set forth in the following general statement, and preferred embodiments of which together with their mode of use are set forth by way of example in the following description, and which are particularly and distinctly pointed out and set forth in the appended claims forming part hereof.

The nature of the improved night depository construction of the present invention or discovery may be stated in general terms as including in combination with other usual parts of a night depository, a pivoted door and a hopper extending from the rear of the door. The hopper includes a bottom wall fixed with respect to the door, and a swinging bottom wall in the hopper is pivoted at the rear end of the fixed bottom wall. The pivoting of the swinging bottom wall is effected by a shaft fixed to the swinging bottom wall and pivoting on the fixed bottom wall. The hopper operates in a hopper compartment which includes a wall adjacent one end of the shaft. An arm is fixed on the shaft end and the arm mounts a cam follower roller. Track cam means are mounted on the adjacent hopper compartment wall, the track cam means including track sections opening towards and receiving and guiding the cam follower roller for effecting movement of the swinging bottom wall relative to the fixed bottom wall during opening and closing of the door.

The cam track sections are four in number and are either curved or angled and connect with each other at corners. Dogs in the cam track sections permit movement of the cam follower roller only in one direction around the four sections, so that the cycle of movements of the parts cannot be reversed.

When the door is closed, the hopper extends downwardly into the hopper compartment and the swinging bottom wall extends across and baffles the chute opening communicating with the

hopper compartment. Opening of the door produces a series of movements of the swinging bottom wall, continuing its baffling action until the door is fully open. At the fully open position of the door, the swinging bottom wall lies substantially parallel with the fixed bottom wall, and the swinging bottom wall is ready to receive a deposited article, and the rear end of the hopper is then in baffling position across the chute opening.

After receiving a deposited article, when the door is being closed, further movements of the swinging bottom wall occur by which the deposited article is ejected from the hopper down into the chute, and the swinging bottom wall is returned to its baffling position across the chute at the final closing of the door.

The various relative movements of the door and hopper and the swinging bottom wall are effected by means of the cam follower on the arm of the swinging bottom wall pivoting shaft and the guiding of the cam follower through the four sections of the cam track.

By way of example, preferred embodiments of the night depository construction of the present improvements are illustrated in the accompanying drawings forming part hereof, in which:

Figure 1 is a vertical sectional view showing a preferred embodiment of the improved night depository construction installed in a bank wall opening, the several parts of the construction being shown in their relative positions when the door is closed;

Fig. 2 is a view similar to Fig. 1 showing the parts when the door is substantially halfway open and just before access to the hopper is about to commence;

Fig. 3 is a view similar to Figs. 1 and 2 showing the parts when the door is fully open;

Fig. 4 is a view similar to Figs. 1, 2, and 3 showing the parts just before final closing of the door;

Fig. 5 is a top plan sectional view as on line 5—5, Fig. 3;

Fig. 6 is a front elevational view looking in the direction of the arrows 6—6, Fig. 3; and

Fig. 7 is a vertical sectional view as on line 7—7, Fig. 3, showing details of the preferred separable track cam plate and its mounting on an apertured side wall of the hopper compartment, and also showing details of parts mounted on the track cam plate.

Similar numerals refer to similar parts throughout the drawings.

One embodiment of the improved night depository construction is indicated generally by 10, and is shown installed in a vertical wall 11 of a building which is usually a bank building, and the wall 11 is usually either an exterior wall or the wall of an entrance hall of the building. Also, the wall 11 is usually solid as shown and made of materials such as masonry or reinforced concrete. The wall 11 has formed therein a rectangular opening 12 and has a front face 13 and a rear face 14.

The improved night depository construction 10 includes a rectangular door frame indicated generally by 15, and walls indicated generally by 16 form a hopper compartment C and extend from the rear of the door frame 15. As shown the door frame 15 includes a front flange 17 extending around a rectangular opening 18, and from the rear face of the front flange 17 and perpendicular thereto there extends a connecting flange 19.

The walls 16 forming the hopper compartment C include a front connecting neck 20 having a

rectangular opening telescoping over and being connected with the flange 19 of the door frame 15. The walls 16 extend from the front connecting neck 20 rearwardly and downwardly and terminate in a rear chute connecting neck 21 extending around a rectangular opening.

The walls 16 forming the hopper compartment C include an upper wall 22 extending from the rear end of the upper wall 23 of the neck 20, and sloping upwardly therefrom, and a lower wall 24 extending from the rear end of the lower wall 25 of the neck 20 and sloping downwardly therefrom. The hopper compartment walls 16 furthermore include vertical side walls 26 and 27. The opening 12 in the building wall 11 has top and bottom faces with sloping portions conforming to and fitting the sloping walls 22 and 24 of the hopper compartment. All the faces of the opening 12 conform to the hopper compartment walls fitted therein.

A door indicated generally by 28 is pivotally mounted adjacent its lower end in the door frame opening 18 by usual means, which as shown include at each side of the door frame a trunnion 29 extending from a door frame side member and pivoting in the bore of a pivot bearing block 30 extending from the rear of the door 28.

When closed, the door 28 fits in the opening 18 of the door frame 15. Adjacent its upper end the door 28 is provided with an outwardly extending pull handle 28-1. There is mounted on the inner face of the door 28, a usual key-operated lock 31 including a bolt 32 extendable into and retractable from a keeper in the top member 33 of the door frame 15, the lock 31 also including a nose 31-1 extending through a cylindrical opening in the door 28, a key cylinder being operative in the nose 31-1 in the usual manner.

Walls extending from the rear of the door 28 form a hopper indicated generally by 34. The hopper forming walls include a vertical wall 35 at one side of the door and a similar vertical wall 36 at the other side of the door. Each of the walls 35 and 36 has the same peripheral shape. Describing the wall 35 in detail, its periphery includes a curved outer edge 37 which extends from a junction with the upper end of the rear face of the door 28 in a circularly curved portion 38 and terminates in a rear straight portion 39 constituting a tangential continuation of the circular portion 38. The rear peripheral corner 40 of the hopper side wall 35 continues as a circular arc from the rear end of the straight edge portion 39, and the periphery of the hopper side wall 35 furthermore includes a straight edge portion 41 extending forwardly from the arcuate corner 40, the straight edge portion 41 being at an angle with the door 28. From the front end of the straight edge portion 41 a notched edge portion 42 extends to the lower side of the door 28. The notched edge portion 42 of the hopper side wall 35 includes an outwardly opening notch 43, and an upwardly extending stop wall 44 is provided on the bottom wall 25 of the hopper compartment in a usual manner, the notch 43 fitting over the stop wall 44 when the door is closed (Fig. 1).

The walls forming the hopper 34 furthermore include a hopper bottom wall 45 extending between the hopper side walls 35 and 36 and having a front flanged end 46 located intermediate the top and bottom ends of the door 28 and a rear end 47 aligned with the rear corners 40 of the side walls 35 and 36. A hopper front end wall 48 extends between the side walls 35 and 36 and upwardly from the bottom wall front

end 46 to a top end 48-1 located intermediate the ends of the circularly curved peripheral portions 38 or the hopper side walls 35 and 36. A cylindrically curved hopper top guard wall 49 extends between the side walls 35 and 36 from the upper end of the door 28 to a curved and flanged rear end 50 which is connected with the upper end 48-1 of the hopper front end wall 48. The hopper walls 35, 36, 45, 48, and 49 are connected with each other at their junctions, preferably by welding; and the hopper side walls 35 and 36 and the hopper top guard wall 49 are connected at their junctions with the rear of the door 28, also preferably by welding.

The foregoing described parts of the depository 10 and their arrangement with each other constitute usual depository construction prior to the present improvements. According to the present improvements, there is located in the hopper 34 a movable and preferably swinging bottom wall indicated generally by 51 which includes a flat rectangular portion 52 having a straight front edge 53, and straight parallel side edges 54 and 55 which are perpendicular to the front edge 53. The edges 54 and 55 extend with close clearance along the inside, respectively, of the hopper side walls 35 and 36, and the edge 53 extends with close clearance along the inside of the hopper front end wall 48 which has a cylindrical curvature as shown. The swinging bottom wall 51 terminates in an angled rear end portion 56 extending rearwardly from a curved corner junction 57 with the rear end of the flat portion 52.

Means pivotally mount the swinging bottom wall 51 on the hopper bottom wall 45 which is fixed with reference to the other hopper walls and the door. As shown the pivoting means constitutes a piano type hinge indicated generally by 58 connecting the rear ends of the fixed bottom wall 45 and the swinging bottom wall 51. As best shown in Fig. 5, the hinge 58 includes spaced cylindrical bends 59 formed on the rear end of the swinging bottom wall 51 and spaced cylindrical bends 60 formed on the rear end of the fixed hopper bottom wall 45, the bends 60 fitting between the bends 59, and the bores of the bends 59 and 60 registering with each other. A pivot or hinge shaft 61 extends through the registering bores of the hinge bends 59 and 60 and also through fitting apertures formed in the rear corners 40 of the hopper side walls 35 and 36.

Each of the swinging bottom wall hinge bends 59 is secured to the shaft 61 as by a pin 62. The shaft 61 includes an end 63 extending beyond the hopper side wall 54 which is spaced from the hopper compartment wall 26, and the shaft end 63 terminates adjacent the hopper compartment wall 26.

Between the hopper side wall 54 and the hopper compartment wall 26 there is located an arm 64 including an end 65 secured on the shaft end 63, and the arm 64 extends from the shaft end 63 towards the door 28, and on the outer end 65 of the arm 64 there is mounted a cam follower roller 67.

The hopper compartment side wall 26 has formed therein an opening 68 as best shown in Figs. 3 and 7. A cam plate 69 is secured in abutment with the outer face 70 on the hopper compartment side wall 26 preferably by bolt and nut sets each indicated by 71. The cam plate 69 has formed therein an endless cam track including track sections each constituted by a straight 75

parallel side groove 72 opening through the hopper compartment side wall opening 68 towards the hopper side wall 54. The cam follower roller 67 is received in and guided by the cam track grooves 72.

The cam track sections connect with each other at corners, and include, as best shown in Fig. 3, a rear track section 73 extending from a lower rear corner 74 to an upper rear corner 75, and an upper track section 76 extending from the upper rear corner 75 to an upper front corner 77, and a front track section 78 extending from the upper front corner 77 to a lower front corner 79, and a lower track section 80 extending from the lower front corner 79 to the lower rear corner 74.

Below the lower cam track section 80 a stop or throw pin 81 extends from the inner face of the hopper compartment side wall 26 towards the hopper side wall 35. As shown in Figs. 3 and 7 the mounting of the pin 81 is effected by means of a mounting plate 82 secured to and depending from the cam plate 69 on the outside of the wall 26. The pin 81 extends through an aperture 83 formed in the wall 26, and the pin 81 includes a reduced threaded outer end 84 extending through an aperture in the plate 82 whereby the shoulder formed between the pin 81 and the threaded end 84 abuts the inside of the plate 82, and a nut 85 is screwed on the threaded end 84 against the outer side of the plate 82.

In the operation of the improved depository construction 10, as will be hereinafter described in detail, it is desirable that the cam follower roller 67 move only in a counterclockwise direction around the four sections of the cam track, as shown in Fig. 3. For preventing reverse or clockwise movement of the cam follower in the cam track sections, one or more of the cam track sections have associated therewith dog means preventing clockwise movement of the cam follower. As shown such dog means are provided for the front track section 78 and the lower track section 80. The front cam plate portion 86 has formed therein a recess having openings 87 and 88 into the front track section 78. In the recess of the cam plate portion 86 there are pivotally mounted dogs 89 and 90 having dog ends extending into the front track section 78, the dogs 89 and 90 being arranged to permit counterclockwise movement of the cam follower 67 in the front track section 78, and prevent clockwise movement thereof. Similarly, a double ended dog 91 is pivotally mounted in a recess formed in the central portion 92 of the cam plate 69, and the dog 91 includes double ends, one of which extends into the track corner 79 and the other of which extends into the lower track section 80, and the double ended dog 91 likewise permits counterclockwise movement of the cam follower 67 from the front track section 78 into the lower track section 80 and from the lower track section 80 to the corner 74, and prevents reverse movement of the cam follower.

As shown and preferably each of the track sections 73, 76, 78, and 80 have different lengths. The upper track section 76 includes two straight angled portions, and the other track sections 73, 78, and 80 are arcuate. From a broader standpoint, each of the track sections 73, 76, 78, and 80 deflects from a straight line.

The chute connecting neck 21 of the hopper compartment as shown is telescoped in and connected with a chute 93 which extends downwardly and communicates with a bank vault, not shown,

where the deposited articles are received. The walls forming the hopper compartment C furthermore include a downwardly sloping rear wall 94 lower portions of which are a rear wall of the chute connecting neck 21.

The operation of the improved night depository construction 10 is as follows:

In Fig. 1 the parts of the night depository construction 10 are shown in their relative positions when the door 28 is closed and locked and with the hopper 34 extending downwardly in the hopper compartment C, the cam follower roller 67 being located in the lower rear corner 74 of the cam track, and the swinging bottom wall 51 being in a position in which its flat portion 52 is substantially vertical and extends across the downwardly sloping chute neck 21 of the hopper compartment, with the front edge 53 of the swinging bottom wall 51 located closely adjacent to the inner face of the hopper compartment rear wall 94. Thus, no deposit can be retained by itself in the hopper or on the bottom wall 51.

In making a deposit, the depositor inserts a key in the lock 31 and retracts the bolt 32 from its keeper in the wall door frame 33, and then swings the door 28 from the closed position shown in Fig. 1 downwardly, and Fig. 2 shows an intermediate position of the door during its opening movement, when the door is substantially half-way open, having been swung substantially 45 degrees from its closed position. At the position of the door shown in Fig. 2 the curved end 50 of the hopper top guard wall 49 has not yet cleared the door frame, and access to the hopper 34 is not yet possible. The cam follower 67 has been pushed up the rear track section 73 swinging the arm 64, the connected shaft 61, and the connected swinging bottom wall 51 in such manner that its front edge 53 moves upwardly in close proximity with the hopper compartment rear wall 94, and the flat portion 52 of the swinging bottom wall 51 takes a position sloping upwardly and substantially parallel with the hopper compartment sloping rear wall 94, when the cam follower reaches the cam track corner 75, as shown in Fig. 2. Thus, any deposit retained on wall 51 by other means will be squeezed between walls 51 and 94 and jam the mechanism.

In Fig. 3, the door is shown fully open, having been swung 90 degrees from its closed position. Access can now be had to the upwardly opening hopper 34. The cam follower 67 has been advanced along the upper track section 76 and has reached the upper front corner 77. During movement of the cam follower along the upper track section 76, the front edge 53 of the swinging bottom wall 51 first advances forward in close proximity to the hopper upper wall 22, and then the swinging bottom wall 51 swings down to the position in which its flat portion 52 is substantially parallel with the hopper fixed bottom wall 45, ready for a deposited article to be received on the top of the flat portion 52 of the swinging bottom wall 51. Meanwhile, the rear 56 of wall 51 and the rear end of wall 45 move close to casing wall 94 to close off any passage through the chute.

After a deposited article has been placed in the hopper on the top of the flat portion 52 of the swinging bottom wall 51, the depositor swings the door 28 upwardly, and the cam follower 67 is advanced down the circular front track section 78 to the cam track corner 79, and the door is then in the position shown in Fig. 4, within about

7 to 8 degrees from its closed position. The center of the circular front track section 78 is on the axis of the door trunnions 29, and consequently there is no relative movement of the swinging bottom wall 51 with respect to the fixed bottom wall 45 as the cam follower 67 advances down the front track section 78.

When the cam follower 67 reaches the cam track corner 79, the arm 64 abuts the stop or throw pin 81, as shown in Fig. 4. During the final closing movement of the door from the position shown in Fig. 4 to the position shown in Fig. 1, the cam follower advances along the lower track section 80 from front to rear, by a coaction 15 of the pin 81 abutting against the arm 64 while the pivot shaft 61 swings forwardly, whereby the swinging bottom wall 51 is rapidly swung from the position shown in Fig. 4 in which the flat portion 52 is substantially parallel with the fixed bottom wall 45 to the chute closing position shown in Fig. 1 in which the flat portion 52 of the swinging bottom wall 51 is angled substantially 30 degrees with respect to the fixed bottom wall 45. If a deposited article has not already slipped from the hopper 34 through the chute neck 21 and into the chute 93, by the time the door and attached parts have reached the positions shown in Fig. 4, the very rapid movement of the swinging bottom wall 51 from the position shown in Fig. 4 to the position shown in Fig. 1 forcibly ejects the deposited article from the hopper 34.

Considering now the improved night depository construction 10 from the standpoint of burglary prevention, it is noted that during an opening movement of the door, the front edge 53 of the swinging bottom wall 51 is first in close proximity to the rear wall 94, and then to the top wall 22 of the hopper compartment as shown in Figs. 1 and 2. Then the rear end portion 56 of the swinging bottom wall 51 comes in close proximity with the rear wall 94. Consequently, at no time during the opening movement of the door is there any substantial space through which a robber might insert hooks or bags suspended on a line or lines over the hopper and into the chute and later remove them with a deposit.

If, however, any such fishing equipment were inserted into the chute 93 during an unauthorized opening of the door 28, when the door is subsequently closed and then opened again for the receipt of a deposited article from an authorized person, and such deposited article is caught on 55 the suspended hooks or bags in the hopper compartment C or the chute 93, if the hooks or bags are located in the chute connecting neck 21, the deposited article caught therein will be jammed when the swinging bottom wall 51 reaches the position shown in Fig. 2, so that the door 28 cannot be opened. If the suspended hooks or bags are lowered down in the chute 93, the upper end of the chute passageway is blocked at every position of the door 28, the hopper 34, and the swinging bottom wall 51 during an opening movement of the door.

As above stated, the dog means associated with the front and bottom track sections 78 and 80 prevent any reverse movement of the door after the door has started to close, with the consequence that the door 28 must be fully closed before any subsequent opening is permitted, and whereby a deposited article is consequently forcibly ejected from the hopper 34 before any subsequent opening of the door is permitted, and

whereby the jamming of the swinging bottom wall 51 against any caught article in the hopper compartment chute connecting neck 21 is insured.

From a broad standpoint the swinging bottom wall 51 may be termed an ejector and baffle member mounted for movement in the hopper 35 by cam follower and cam means operative between the ejector and baffle member and an adjacent wall of the hopper compartment. Likewise, from a broader standpoint, the connection between the hopper 34 and the door 28 may be made in any desired manner so as to cause the hopper to swing with the door.

In the foregoing description, certain terms have been used for brevity, clearness, and understanding, but no unnecessary limitations are to be implied therefrom beyond the requirements of the prior art, because such words are used for descriptive purposes herein and are intended to be broadly construed.

Moreover, the embodiments of the improved construction illustrated and described herein are by way of example, and the scope of the present invention is not limited to the exact details of construction.

Having now described the invention or discovery, the construction, the operation, and use of preferred embodiments thereof, and the advantageous new and useful results obtained thereby; the new and useful constructions, and reasonable mechanical equivalents thereof obvious to those skilled in the art, are set forth in the appended claims.

I claim:

1. In night depository construction and the like including opposite side walls and other walls forming a hopper compartment having a door frame front opening and a chute neck rear opening, a door, means pivoting the door adjacent its lower side in the door frame front opening, a hopper extending from the rear of the door, and the hopper including a first bottom wall; the combination including a swinging hopper bottom wall, shaft means fixed to and pivoting the swinging bottom wall on the first bottom wall, and means operatively associating the shaft means and one of the side walls of the hopper compartment for oscillating the shaft means and the swinging bottom wall relative to the first bottom wall, the hopper compartment walls and the door frame front opening during opening and closing of the door.

2. In night depository construction and the like as set forth in claim 1, and in which the shaft means fixed to and pivoting the swinging bottom wall on the first bottom wall is at the rear end of the first bottom wall.

3. In night depository construction and the like as set forth in claim 1, and in which the shaft oscillating means are operative to permit movement of the door from the closed position to the open position and from the open position to the closed position and in which means are included preventing reverse movements of the door after a closing movement has commenced.

4. In night depository construction and the like as set forth in claim 1, and which includes dog means associated with the shaft oscillating means and operative to permit movement of the door from the closed position to the open position and from the open position to the closed position and preventing reverse movements of the door after a closing movement has commenced.

5. In night depository construction and the like as set forth in claim 1, and in which the means for oscillating the shaft means include a cam follower operatively connected with the shaft means and a cam for guiding the cam follower, the cam being located on said one side wall of the hopper compartment.

6. In night depository construction and the like as set forth in claim 1, and in which the means for oscillating the shaft means include a cam follower operatively connected with the shaft means and a cam for guiding the cam follower, the cam being located on said one side wall of the hopper compartment, and dog means associated with the cam and permitting movement of the cam follower so as to permit movement of the door from the closed position to the open position and from the open position to the closed position and preventing reverse movement of the cam follower and reverse movements of the door after a closing movement has commenced.

7. In night depository construction and the like including walls forming a hopper compartment having a door frame front opening and a chute neck rear opening, a door, means pivoting the door adjacent its lower side in the door frame front opening, a hopper extending from the rear of the door, and the hopper including a first bottom wall; the combination including a swinging bottom wall in the hopper, means pivoting the swinging bottom wall on the first bottom wall, the pivoting means including a shaft fixed to the swinging bottom wall and pivoting on the first bottom wall, the hopper operating in the hopper compartment and the hopper compartment forming walls including a side wall adjacent one end of the shaft, an arm fixed on the shaft end, a cam follower roller mounted on the arm, track cam means mounted on the hopper compartment side wall, the track cam means including track sections opening towards and receiving and guiding the cam follower roller for oscillating the shaft and the swinging bottom wall relative to the first bottom wall, the hopper compartment walls and the door frame opening during opening and closing of the door.

8. In night depository construction and the like as set forth in claim 7, and in which there are four cam track sections which connect with each other at corners.

9. In night depository construction and the like as set forth in claim 7, and in which there are four cam track sections which connect with each other at corners, and in which each track section deflects from a straight line.

10. In night depository construction and the like as set forth in claim 7, and in which there are four cam track sections which connect with each other at corners, and in which each track section has a different length than the others.

11. In night depository construction and the like as set forth in claim 7, and in which there are four cam track sections which connect with each other at corners, the four track sections constituting in sequence a rear track section extending from a lower rear corner to an upper rear corner, an upper track section extending from the upper rear corner to an upper front corner, a front track section extending from the upper front corner to a lower front corner, and a lower track section extending from the lower front corner to the lower rear corner.

12. In night depository construction and the

like as set forth in claim 7, and in which there are four cam track sections which connect with each other at corners, the four track sections constituting in sequence a rear track section extending from a lower rear corner to an upper rear corner, an upper track section extending from the upper rear corner to an upper front corner, a front track section extending from the upper front corner to a lower front corner, and a lower track section extending from the lower front corner to the lower rear corner, the upper track section being angled and each of the other track sections being curved.

13. In night depository construction and the like as set forth in claim 7, and in which there are four cam track sections which connect with each other at corners, the four track sections constituting in sequence a rear track section extending from a lower rear corner to an upper rear corner, an upper track section extending from the upper rear corner to an upper front corner, a front track section extending from the upper front corner to a lower front corner, and a lower track section extending from the lower front corner to the lower rear corner, the upper track section being angled and each of the other track sections being arcuate.

14. In night depository construction and the like as set forth in claim 7, and in which there are four cam track sections which connect with each other at corners, the four track sections constituting in sequence a rear track section extending from a lower rear corner to an upper rear corner, an upper track section extending from the upper rear corner to an upper front corner, a front track section extending from the upper front corner to a lower front corner, and a lower track section extending from the lower front corner to the lower rear corner, and a stop pin extending from the hopper compartment wall mounting the track cam means, the stop pin being located below the lower track section and being adapted for abutment by the arm on the pivoting shaft as the cam follower moves through the lower track section.

15. In night depository construction and the like including opposite side walls and other walls forming a hopper compartment having a door frame front opening and a chute neck rear opening, a hopper, means pivotally mounting the hopper in the hopper compartment, a door connected to the hopper and movable into and out of closed position in the door frame front opening and the hopper having an upper opening and pivoting with movements of the door so as to position the upper opening into and outside of the hopper compartment and the door frame front opening thereof; the combination including an ejector and baffle member in the hopper, means on the hopper mounting the ejector and baffle member for movement with respect to the hopper, and means operatively associating the ejector and baffle member and one of the side walls of the hopper compartment for moving the ejector and

baffle member with respect to the hopper, the hopper compartment walls and the door frame front opening during opening and closing of the door.

5 16. In night depository construction and the like as set forth in claim 15, and in which the movements of the ejector and baffle member are in repeating cycles during movements of the door from the closed position to the open position and 10 from the open position to the closed position.

17. In night depository construction and the like as set forth in claim 15, and in which the movements of the ejector and baffle member are 15 in repeating cycles during movements of the door from the closed position to the open position and from the open position to the closed position, said movements of the ejector and baffle member positioning the ejector and baffle member so as to block passage from the hopper compartment front opening to the chute neck rear opening at the closed position of the door and during opening movement of the door and so as to eject a deposited article from the hopper during the final closing movement of the door.

20 18. In night depository construction and the like including opposite side walls and other walls forming a hopper compartment having a door frame front opening and a chute neck rear opening, a door and hopper member, means pivotally mounting the door and hopper member in the hopper compartment, the hopper having an upper opening located inside the hopper compartment when the door and hopper member is closed and outside the door frame when the door 25 and hopper member is open; the combination including an ejector and baffle member in the hopper, means on the hopper mounting the ejector and baffle member for movement with respect to the hopper, and means operatively associating the ejector and baffle member and one of the side 30 walls of the hopper compartment for moving the ejector and baffle member with respect to the hopper, the hopper compartment walls and the door frame front opening during opening and 35 closing of the door and hopper member.

40 HERBERT C. BEHRENS.
